UNITED STATES PATENT OFFICE.

PAUL ANDERSON, OF VASTERAS, SWEDEN.

MACHINE FOR THE SINTERING OF ORE AND THE LIKE.

Application filed November 16, 1926, Serial No. 148,739, and in Sweden August 1, 1926.

My invention relates to a machine intended for the sintering (agglomerating) of dressed ore, as for instance slime and the like, with the aid of the known process, according to which a current of air is caused to pass through a mixture of ore and a suitable fuel, as for instance coal dust and the like, which is ignited at its surface by means of oil, a gas flame, a glowing fuel, or the like.

The invention is illustrated diagrammatically and by way of example on the accompanying drawing on which Figure 1 is a plan of a sintering or agglomerating machine designed according to this invention, and Figure 2 is a vertical section through the same in the plane X—X of Fig. 1, this Figure (2) being drawn to an enlarged scale and showing only one half of the machine.

On the drawing, *v* denotes a circular frame carrying a plurality of sintering pans *a* arranged in a circle. The frame *v* with its pans *a* can be turned around a centrally arranged suction vessel *b*. Each pan is provided with a grate *w*; the pan portion located below the grate is of hopper-like shape, and from the centre of this portion extends a suction pipe *t* connected at its other end with a horizontal branch pipe *d* of a vertical casing *c* secured to a plate closing the vessel *b*.

In the sintering or agglomerating machines of the type in question as hitherto designed the branch *d* and the end of the tube *t* were connected turnably with each other by means of a suitably designed coupling permitting tipping and inverting the respective pan in order to empty it in this way. Experience has, however, shown that this construction does not render possible maintaining the proper shape of the pan and has, therefore, proved unsuited for practical employment.

Now, according to the present invention the connection between the suction pipe of each pan and the branch *d* has been rendered disconnectible, in such a manner, that the tipping axis of each pan forms a larger or smaller angle, preferably a rectangle, with the tube axis at the place of connection. It has been found that a connection of this kind can be kept perfectly tight even if the shape of the pan has undergone considerable changes, and it is now rendered possible to make the pans of sheet-metal,

whereas formerly cast iron, if not cast steel, was necessary. Besides that advantage, another is attained by the simple radial arrangement of the stationary tube branch *d*, and resides therein that the tipping takes places about a tangential axis whereby it is rendered possible that the operator who stands upon the neighboring stationary platform can tilt each pan with one of his feet.

The most exterior part *l* of the branch *d* is preferably shiftable with respect to the other part (*d* proper), and tightened relatively to it by means of a stuffing box *m*. Preferably a packing *n* is inserted into the joints between the branch portion *l* and the suction pipe *t*, and a lever *s* is provided by means of which the branch portion *l* can be withdrawn from the tube *t*.

The casings *c* are valve casings, there being a valve provided for each suction pipe and located between it and the common suction vessel *b*. This vessel is rotatory on the top of a stationary suction pipe *p* provided with a stuffing box *r* for tightening it.

I claim:

1. An ore sintering machine, comprising, in combination, a horizontal rotatory frame, sintering pans distributed around the axis of said frame and being adapted to be tilted around horizontal axes lying at substantially right angles to the radii extending from the frame axis to the mid points of said pans; suction pipes extending from the bottom of the pans radially inwards with the respect to said frames and other suction pipes extending from the center portion of the said frame radially outwards and communicating each with one of the pan suction pipes.

2. An ore sintering machine, comprising, in combination a horizontal rotatory frame, sintering pans distributed around the axis of said frame and being adapted to be tilted around horizontal axes lying at substantially right angles to the radii extending from the frame axis to the mid points of said pans; suction pipes extending from the bottoms of the pans radially inwards with the respect to said frame and other suction pipes extending from the center portion of said frame radially outwards and communicating each with the one of the pan suction pipes each of said other suction pipes consisting of two telescopically arranged parts, of which the outer one is that communicat-

ing with the appertaining pan suction pipe, said part being adapted to be withdrawn from the respective pan suction pipe.

3. An ore sintering machine, comprising,
  - 5 in combination, a horizontal rotatory frame, sintering pans having each a hopper-shaped bottom and being distributed around the axis of said frame and being adapted to be tilted around horizontal axes lying at substantially right angles to the radii extending from the frame axis to the mid point of said pans; suction pipes extending from the center portion of said pan bottoms radially inwards with respect to said frame and other suction pipes extending from the center portion of the said frame radially outwards and communicating each with one of the pan suction pipes.
  - 10
  - 15

4. An ore sintering machine, comprising,

in combination, a horizontal rotatory frame, 20 sintering pans distributed uniformly around the axis of said frame and being adapted to be tilted around horizontal axes lying at substantially right angles to the radii extending from the frame axes to the mid 25 points of said pans; suction pipes extending from the bottoms of the pans radially inwards with respect to said frame and other suction pipes extending from the center portion of the said frame radially outwards and communicating each with one of the pan suction pipes, a centrally located common suction chamber provided in the said frame and communicating with all said other suction pipes, and valves inserted into 30 these pipes, substantially as set forth.

In testimony whereof I affix my signature.

PAUL ANDERSON.
